CLAIM

I claim the ornamental design for a lamp head, as shown and described.

DESCRIPTION

FIG. 1 is a perspective view of the lamp head showing the new design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken lines in the figures show portions of the lamp head that form no part of the claimed design.

1 Claim, 4 Drawing Sheets
